ADJUSTABLE GUIDE FOR FLAME HARDENING TORCHES

Frederick W. Riedel, Belle Vernon, Pa.

Application February 8, 1945, Serial No. 576,803

2 Claims. (Cl. 266—5)

1

The present invention relates to improved features of construction and arrangement of guiding means for a flame hardening torch such as used to harden, temper, or otherwise heat treat a metal workpiece. Such flame hardening torches are broadly old, and the herein claimed improvement is directed chiefly to a novel torch guide inclined to the longitudinal axis of the work, means for urging a follower member secured to the torch into engagement with the guide, supporting means for adjustably varying the elevation of the guide, and means for adjusting the angularity of the guide with relation to said supporting means.

While not limited thereto, the embodiment of the invention illustrated is peculiarly well suited for guiding a pair of oppositely disposed flame hardening torches along converging straight lines paralleling the opposite faces of each longitudinally tapered tooth of a bevel gear which is so mounted in a normally fixed chuck that each tooth can be successively brought to position to be acted upon by the torches.

For a more complete understanding of the invention, reference should be made to the accompanying drawings, the following detailed disclosure, and the appended claims.

In the drawings:

Figure 1 is a plan view illustrating an embodiment of the invention as combined with a pair of flame hardening torches and the means for supporting them with provision for movement both longitudinally and transversely of the work to be flame hardened.

Figure 2 is an enlarged plan view of the torch guides and their supporting means.

Figure 3 is a side elevation of the apparatus, omitting the torches and their supporting carriage.

Figure 4 is an end elevation of Figure 3 as viewed from the left.

Figure 5 is a cross-sectional elevation taken on line V—V of Figure 3.

Figure 6 is a fragmentary detail section on line VI—VI of Figure 3.

Figure 7 is a skeleton view in side elevation, illustrating the invention as applied to the flame hardening of a tapered workpiece such as a bevel gear.

Referring to the embodiment of the invention illustrated, reference numeral 10 represents a movable carriage supporting a pair of duplicate oppositely disposed flame hardening torches indicated generally at 12, each of which includes a flame directing nozzle 14. Each flame hard-

2

ening torch is so supported by the carriage 10 that it can be moved relatively to its mate, and each can be individually raised and lowered by a suitable adjusting screw carrying a hand-wheel 15 which operates a vertically movable torch supporting slide 16 mounted in guides 17 mounted on the carriage.

The carriage 10 is adapted to be moved manually in a horizontal plane along guides 11 toward and from the workpiece W, and the torches 12 are mounted on the carriage in such manner as to be movable in opposite directions transversely of the longitudinal movement of the carriage. As illustrated by way of example in the drawings, the blow-pipes 13, forming part of the torches, are secured to the slides 16, and these pipes are sufficiently flexible to permit the nozzles 14 to move transversely of the line of travel of the carriage. Such transverse movement of the torch nozzles is effected by a relatively stiff steel spring loop 19 engaging the blow-pipes 13—13, as shown in Figure 6.

As shown in Figures 3 and 5, the work to be flame hardened is a bevel gear W, having a plurality of teeth indicated at t. The opposite walls t' of each tooth taper from the butt end of the gear toward the front end thereof. The present invention makes available precision means for accurately guiding the nozzles 14 of the torches 12 in paths parallel to the converging faces t, t' of each tooth, and in proper spaced relation thereto.

Each torch includes a water pipe 18 to convey a coolant which is adapted to be discharged at a point to the rear of that where the flame emerges from the nozzle, so as to quench the work immediately after subjecting it to the flame hardening action. Such simultaneous flame hardening and quenching means are old in the art, and are not claimed herein apart from the combination as shown and described.

Secured to the blow-pipe 13 of each torch is a follower 20 adjustably positioned by means of a clamp bolt 22. The inner end of each follower 20 is provided with a half-round notch 24 for engagement with a cylindrical guide rod 26. The guide rods 26, as best shown in Figure 2, are in converging relation so that they substantially parallel the converging faces t, t' of the gear teeth to be heat treated. The angular position of each guide rod 26 may be varied to suit the taper of different gear teeth. To this end I rigidly secure fittings 28 and 30 adjacent the extremities of the guide rods 26, these fittings being provided with threaded openings to re-

ceive bolts 32 and 34 which pass through slots 36 and 38 formed in a guide rod supporting bar 40 which in turn is secured by fastening means 42 to the extremities of the supporting rod 44. The rod 44 is of cylindrical stock and is formed with a flattened seat 41 at one end for engagement with the supporting bar 40 which is of rectangular cross section. The rod 44 is adjustably secured in the split hub extension 46 of a bracket 50 by a clamp bolt 48, the hub being welded or otherwise secured to the bracket. The bracket 50 includes a vertically disposed hub 52 which is split at 54 and provided with a clamp bolt 56 for adjustably securing the bracket at any desired elevation along the length of a standard 58 which is welded or otherwise secured at its lower end to a horizontally movable slide 60 positioned in a guide groove 62 of a base member 64 which is secured by suitable fastening devices 66 to any fixed structure such as indicated at 68.

Paralleling the standard 58 is a feed screw 70 having a rounded lower end 72 seated in a bearing block 74 carried by the slide. The feed screw 70 engages a threaded feed nut portion 76 formed integrally on the adjustable bracket 50. At its upper end the feed screw is provided with a collar 78 and with a cylindrical bearing portion 80, the latter passing freely through a bearing lug 82 secured to a cap fitting 84 welded or otherwise secured to the upper extremity of the standard 58. A hand-wheel 86 secured to the upper end of the feed screw 70 provides means for manually adjusting the elevation of the bracket guide rod 44 and the bar 40 secured thereto.

An adjusting screw 88 engages a suitable threaded aperture 90 formed in the slide 60, said screw being rotatably mounted in an upstanding lug 92 formed on the base 64 and carrying a knurled adjusting knob 94 which when manipulated will serve to shift the slide toward or from the work W which may be regarded as fixedly mounted in a chuck 96 which is arranged to be periodically turned on the axis x-y of the work such as the bevel gear illustrated in Figure 7, so as to successively bring each tooth into position for flame hardening. The chuck is capable of rotary adjustment about axis x-y, and is adapted to be angularly adjusted about a pivot pin 98 secured to a suitable chuck base 100 carrying means such as a pivotally mounted bolt 102 for adjustably holding the chuck in various angular positions to suit the taper of the particular bevel gear to be heat treated.

In operation, assuming that it is desired to separately flame harden each individual tapered tooth of a bevel gear, the gear is rotatably mounted in a chuck such as shown in Figure 7, with the axis of rotation x-y of the gear disposed at such angle that the base of the uppermost tooth lies in a horizontal plane. This is desirable since the torch-supporting carriage moves in a horizontal plane along the horizontally disposed guides 11.

The provision of an adjustably mounted work-holding chuck makes it possible to readily adapt the apparatus for the flame-hardening of different tapers of bevel gears without disturbing the straight-line horizontal travel of the carriage. For the precision flame hardening of the tapered teeth of a bevel gear, a problem is involved due to the taper of the tooth, and this problem becomes more complex by reason of the fact that a great number of differently tapered bevel gears are required to suit various demands of the trade.

The invention overcomes the problem by the provision of unique mounting means for the converging guides 26-26. These guides are adapted by means described in detail to be set easily and quickly in such converging relation that the included angle between them is substantially the same as the taper of each tooth of the bevel gear at the pitch line thereof. Thus when changing the size of the workpiece or when changing the set-up to suit different gears, it is merely necessary to properly vary the included angle between the guides 26-26. Because the depth of teeth on the bevel gears will vary with different size gears, the described mechanism is provided with the means shown and described for adjusting the elevation of the guide-supporting rod 44, and for a similar reason the standard which supports the guide-carrying rod can also be shifted in a lengthwise direction toward and from the work. Thus practically universal adjustment of the guides can be easily and quickly made, making possible the setting of the torch guide with great precision to suit the angularity of a wide variety of teeth of bevel gears of different pitch diameters and tapers. This is in marked contrast with the prior art practice which, in so far as I am aware, required the operator to manually guide the flame hardening torch during its travel lengthwise of each individual tooth.

In the machine illustrated, the torch-supporting carriage moves in a horizontal plane, and the rotatable work-holding support has been referred to as inclined to the horizontal. It will be understood, however, that the entire apparatus may be turned 90° so that the carriage can move vertically without in any way affecting the mode of operation of the invention.

While I have described quite specifically the construction and arrangement of parts in the embodiment of the invention illustrated, it is to be understood that various modifications and substitutions of equivalents may be made by those skilled in the art without departure from the spirit and scope of the invention as defined in the appended claims.

I claim:

1. Torch guiding means of the character described, comprising a standard having a bracket vertically adjustable thereon, a member adjustably horizontally with respect to said bracket, a supporting bar secured to said member, guide rods carrying fittings at their ends, means adjustably securing said fittings to said supporting bar, followers notched for guiding engagement with said guide rods, and means yieldingly urging said followers into guiding engagement with said guide rods.

2. Torch guiding means of the character described, comprising a vertical standard, a bracket slidably therealong having securing means for clamping it at various elevations, a member slidably horizontally in said bracket, means for clamping said member in desired positions of adjustment, a supporting bar secured to said member, guide rods carrying fittings at their extremities, means adjustably securing the fittings to the supporting bar constructed and arranged to provide for variation in the angularity of the guide rods with respect to the supporting bar, followers notched for guiding engagement with said guide rods, and resilient means for urging said followers into engagement with said guide rods.

FREDERICK W. RIEDEL.
